Patented Aug. 27, 1918.

UNITED STATES PATENT OFFICE.

JOHN W. JEPSON, OF DEPEW, NEW YORK, ASSIGNOR TO GOULD COUPLER COMPANY, A CORPORATION OF NEW YORK.

IGNITION SYSTEM.

1,277,078.

Specification of Letters Patent. Patented Aug. 27, 1918.

Application filed July 9, 1915. Serial No. 38,848.

To all whom it may concern:

Be it known that I, JOHN W. JEPSON, a citizen of the United States, and a resident of Depew, county of Erie, and State of New York, have invented certain new and useful Improvements in Ignition Systems, of which the following is a specification.

My invention relates to ignition systems and more particularly to ignition systems for the ignition of gas engines. It is especially applicable to the ignition of gas engines driving automobiles.

The general object of my invention is to provide such a system which is not only simple in construction and operation but which is more efficient. To this end I provide a system having a battery and generating armature for feeding the ignition circuit and charging the battery and so arranged that as the speed of the engine and the armature driven thereby is increased on starting, the voltage produced by the armature is added to that of the battery to cause the ignition circuit to more quickly build up so that a more efficient ignition is obtained at such time. As a further feature I arrange the parts so that current through the interrupter or induction coil feeding the sparking devices or both is alternated in direction, thereby preventing the building up of the platinum points, contacts or electrodes by the sparks passing thereacross.

Further objects, features and advantages will more clearly appear from the following description taken in connection with the accompanying drawings which form a part of this specification.

In the drawings, Figures 1 and 2 are diagrams illustrating one embodiment of my invention;

Figs. 3 and 4 are diagrams illustrating a modification; and

Fig. 5 illustrates another embodiment.

Referring to Fig. 1, 1 represents the secondary high tension winding of an induction coil having one terminal 2 connected to the ground, the other terminal 3 being adapted to be connected to sparking devices to supply or feed the same in a well known

manner. The primary 4 of the induction coil is connected in series in an ignition circuit in series with a storage battery 5, armature winding 6, interrupter 7 and commutator 8 provided with contact portions 9 and 10. A cam 11 operates the interrupter 7 in a well known manner, and a condenser 12 is placed in shunt about the interrupter. A lamp or work circuit 40 is shown connected across the battery to be supplied thereby when the generating armature is not running at sufficient speed. The ignition circuit may be traced as follows: from the positive side of the battery 5, through the primary 4 of the induction coil, brush 13, contact 9, armature or magneto winding 6, brush contact 16, interrupter 7, brush 14, contact 10, brush 15 and to ground to which the negative side of the battery is connected. The armature windings 6 are preferably of the magneto type although carried by an armature structure 17 provided with another set of armature windings connected to a commutator 18 having brushes 19 and 20, the latter being connected to the ground and the former to the positive side of the battery through a series field coil 21 opposing the shunt fields 22 which set up the necessary field for the armature. In this way the armature windings connected to the commutator will act to supply current to charge the battery and supply the work circuit 40 when running at sufficient speed. Suitable automatic and hand switches may be provided for disconnecting the battery from the commutator 18 when the battery has been charged and for opening the ignition circuit when not in use. Instead of opening the charging circuit when the battery has been charged, the charging current may be automatically reduced or eliminated in any suitable or well known manner, leaving the commutator still connected in circuit.

When the engine for which the ignition system is designed is being started the battery supplies the necessary current through the ignition circuit above described sufficiently to energize the primary 4 of the in-

duction coil to produce the required sparks at the sparking devices. Under these conditions the magneto armature winding 6 produces practically no voltage. As the engine 5 speeds up and so drives the armature 17 an electromotive force is generated in the windings 6 which, by reason of the commutator 8, is always in the same direction as that of the battery 5 in the ignition circuit above 10 described. Fig. 2 illustrates the circuit connections with the electromotive force produced in the windings 6 in the opposite direction from what it was under the conditions of Fig. 1. The ignition circuit in Fig. 15 2 may be traced as follows: from the positive side of the battery 5, through primary 4, brush 13, contact 10, brush 14, interrupter 7, brush contact 16, armature winding 6, contact 15 to ground and the negative side 20 of the battery. Thus the commutator 8 alternately connects the battery and magneto armature windings 6 whereby the voltage of one is in the same direction as the voltage of the other in the ignition circuit whereby the 25 voltage of the ignition circuit increases with the speed of the magneto. That is, the commutator 8 reverses periodically the connections between the battery and armature windings 6 so that the voltage generated by 30 the latter and the battery will be in the same direction and cause the ignition circuit to quickly build up. This is important because as the speed of the engine increases with the consequent lessening of the interval of time 35 between sparks a lesser amount of time is given for energizing the induction coil, but with my arrangement the full energization of the induction coil is obtained because as the speed increases the windings 6 add an 40 increasing electromotive force to that furnished by the battery to build up and energize the ignition circuit and induction coil.

As shown in Figs. 1 and 2, the induction coil is connected on the battery side of 45 the commutator 8 so that the primary 4 always builds up with current in the same direction. The interrupter 7, however, is connected on the magneto armature winding side of the commutator 8 so that the current 50 through the interrupter will alternate at each building up of the ignition circuit, thereby preventing the platinum points or contacts of the interrupter from building up by the carrying of particles from one to the 55 other always in the same direction, as is the case when the current passes through such an interrupter always in the same direction.

The system illustrated in Figs. 3 and 4 is the same as that of Figs. 1 and 2 except 60 that the induction coil is connected on the magneto armature winding side of the commutator 8 instead of on the battery side thereof, so that the current in the primary winding 4 of the induction coil builds up the 65 coil in alternate directions. The ignition

circuit in Fig. 3 may be traced as follows: from the positive side of the battery 5, through the brush 13, contact 10, brush 14, interrupter 7, primary 4, brush contact 16, armature windings 6, contact 9, and brush 15 70 to ground to the negative side of the battery. When the magneto windings 6 build up in the opposite direction the current in windings 4 and interrupter 7 is in the opposite direction, the circuit being traced as follows: 75 from the positive side of the battery through brush 13, contact 9, windings 6, brush contact 16, primary 4, interrupter 7, brush 14, contact 10, and brush 15 to ground to the negative side of the battery. 80

In each case the electromotive force produced by the windings 6 is added to that of the battery, causing the ignition circuit and induction coil to build up more quickly as the speed increases and as time given for 85 building up is decreased. If desired, the interrupter 7 may be placed on the battery side of the commutator 8, but as above pointed out, this is not so advantageous.

The arrangement shown in Fig. 5 is the 90 same as that shown in Fig. 1 except that the interrupter 7 and commutator 8 are combined in one apparatus. As there shown, the interrupter 25 is carried upon a disk 26 rotated in synchronism with the engine 95 and armature 17. Each time the disk 26 makes a half revolution one of the relatively stationary rollers 27 engages one arm 28 of the interrupter, causing the interrupter contacts to be separated, a condenser 29 being connected in shunt about the interrupter contacts. The disk 26 carries two contacts 30 and 31 adapted to contact with stationary brushes 32 and 33 alternately as the parts rotate. The brush 33 is connected to 100 ground, the contact 31 is connected to one of the interrupter contacts 34, while the other interrupter contact 35 is connected to one terminal of the magneto armature windings 6, the other terminal of which is connected to the contact 30. The ignition circuit may be traced as follows: from the positive side of the battery through the primary 4, brush 32, contact 30, windings 6, interrupter contacts 35, 34, contact 31 and 105 brush 33 to ground and the negative side of the battery. Upon reversal of electromotive force in windings 6, the contacts 30 and 31 will be in reverse position, so that the current building up the induction coil 110 will pass from the battery and primary 4, through brush 32, contact 31, interrupter contacts 34, 35 (in the opposite direction from what it was before) windings 6 (in the opposite direction also) contact 30 and 115 brush 33 to ground and the negative side of the battery. The combined interrupter and commutator of Fig. 5 may be substituted in the systems of any of the other figures, and many other changes and modifica- 120 125 130

tions may well be made without departing from the spirit and scope of my invention in its broader aspects.

Having fully and clearly described my invention, what I claim as new and desire to secure by Letters Patent, is:

1. A system of the class described having an ignition circuit containing a battery, magneto armature and interrupter in series with one another, a commutator acting to so effect connection of the battery and magneto armature that the voltage of one is maintained in the same direction as the voltage of the other in said circuit whereby the 15 voltage of the ignition circuit increases with the speed of the magneto, a work circuit, and armature windings driven synchronously with the magneto armature and connected to charge the battery and supply the 20 work circuit when running at sufficient speed.

2. A system of the class described having an ignition circuit with a battery, magneto armature and interrupter in said circuit, a 25 commutator acting to reverse the connections between the battery and magneto armature so that the voltage of each will always be in the same direction to build up the ignition circuit, and armature windings 30 connected in circuit with the battery to charge the battery when running at sufficient speed.

3. A system of the class described having a generating armature, a battery and an 35 ignition circuit in operative relation, and a commutator reversing the connections between the battery and armature so that the voltage generated by the armature and battery will be in the same direction to build up 40 the ignition circuit, said generating armature having windings connected to charge the battery when running at sufficient speed.

4. A system of the class described having an ignition circuit with a battery and 45 generating armature in series therein, a commutator reversing the connections between the battery and armature so that the voltage generated by the armature and battery will be in the same direction to build 50 up the ignition circuit as the speed of the armature increases, said generating armature having windings connected to charge the battery when running at sufficient speed, and a work circuit connected across the battery to be supplied by the said last-mentioned armature windings and battery.

5. A system of the class described having an ignition circuit operating with a battery, generating armature and induction 60 coil in series therein and in series with one another, the induction coil having a secondary circuit adapted to feed sparking devices, said generating armature having windings connected to charge the battery 65 when running at sufficient speed, and a work

circuit connected across the battery to be supplied by the said last-mentioned armature windings and battery.

6. A system of the class described having a generating armature, a battery and an 70 ignition circuit in series, an induction coil in series in said circuit, the secondary of which is adapted to supply sparking devices, and a commutator reversing the connections between the battery and armature so that 75 the voltage generated by the armature and battery will be in the same direction to build up the ignition circuit and means on said armature for feeding a work circuit.

7. A system of the class described having 80 an ignition circuit with a battery, generating armature and interrupter in series therein, a commutator reversing the connections between the battery and armature so that the voltage generated by the armature and 85 battery will be in the same direction to build up the ignition circuit, and an induction coil in said circuit the secondary of which is adapted to supply sparking devices.

8. A system of the class described having 90 an ignition circuit, a battery, generating armature, and interrupter all in series, and a commutator reversing the connections between the battery on the one hand and the armature and interrupter on the other hand 95 so that the voltage generated by the armature and battery will be in the same direction to build up the ignition circuit but the current through the interrupter will alternate in direction, and means automatically 100 charging said battery.

9. A system of the class described having an ignition circuit with a battery, generating armature, commutator and interrupter all 105 operating in series with one another, a secondary circuit in inductive relation to said ignition circuit, and means revolving with the generating armature and adapted to charge the battery.

10. A system of the class described having 110 an ignition circuit, a battery, generating armature, commutator and interrupter all in series with one another, and a secondary circuit in inductive relation to said ignition circuit, said commutator reversing the connections between the battery on the one hand and the armature and interrupter on the other hand so that the voltage generated by the armature and battery will be in the same direction to build up the ignition circuit but 115 the current through the interrupter will alternate in direction, and a winding on said armature for charging the battery.

11. A system of the class described having an ignition circuit with a battery, generating 125 armature, interrupter and induction coil in operative relation thereto, and a commutator reversing the connections between the battery on one hand and the armature, interrupter and induction coil on the other hand, 130

- whereby the voltage generated by the armature and battery will always be in the same direction to build up the ignition circuit but the current through the interrupter and induction coil will alternate in direction. 5
12. A system of the class described having an ignition circuit with a battery, generating armature and induction coil in operative relation thereto, and a commutator reversing the connections between the battery on one hand and the armature and induction coil on the other hand, whereby the voltage generated by the armature and battery will always be in the same direction to build up the ignition circuit but the current through the induction coil will alternate in direction. 10
13. A system of the class described having an ignition circuit with a battery, generating armature, interrupter and induction coil in series therein and in series with one another, and a commutator reversing the connections between the battery on one hand and the armature, interrupter and induction coil on the other hand, whereby the voltage generated by the armature and battery will always be in the same direction to build up the ignition circuit but the current through the interrupter and induction coil will alternate in direction. 15
14. A system of the class described having an ignition circuit with a battery, generating armature and induction coil in series therein and in series with one another, the induction coil having a secondary circuit adapted to feed sparking devices, and a commutator reversing the connections between the battery on one hand and the armature and induction coil on the other hand, whereby the voltage generated by the armature and battery will always be in the same direction to build up the ignition circuit but the current through the induction coil will alternate in direction. 20
15. A system of the class described having an ignition circuit with a battery, generating armature and induction coil in operative relation thereto, the induction coil having a secondary circuit adapted to feed sparking devices, and a commutator reversing the connections between the battery on one hand and the armature and induction coil on the other hand, whereby the voltage generated by the armature and battery will always be in the same direction to build up the ignition circuit but the current through the induction coil will alternate in direction. 25
16. A system of the class described having an ignition circuit with a battery, generating armature and induction coil in series therein and operating in series with one another, the induction coil having a secondary circuit adapted to feed sparking devices. 30
17. A system of the class described having an ignition circuit with a battery, generating armature, interrupter and induction coil in series therein and in series with one another, the induction coil having a secondary circuit adapted to feed sparking devices. 35
18. A system of the class described having an ignition circuit, a battery, generating armature and induction coil all in series with one another, and a commutator reversing the connections between the battery and armature so that the voltage generated by the armature and battery will be in the same direction to build up the ignition circuit, the induction coil having a secondary circuit adapted to feed sparking devices, and the armature having a winding thereon for feeding a work circuit. 40
19. A system of the class described having an ignition circuit with a battery adapted to feed the same and an interrupter in operative relation thereto, a generating armature having two windings, one coöperating with the battery to feed the ignition circuit and one connected to charge the battery, and a secondary circuit in inductive relation to said ignition circuit. 45
20. A system of the class described having an ignition circuit with a battery adapted to feed the same and an interrupter in operative relation thereto, a generating armature having two windings, one coöperating with the battery to feed the ignition circuit and one connected to charge the battery, and an induction coil in the ignition circuit having a secondary adapted to feed sparking devices. 50
21. A system of the class described having an ignition circuit with a battery adapted to feed the same and an interrupter in operative relation thereto, a generating armature having two windings, one connected to feed the ignition circuit and one connected to charge the battery, and a commutator reversing the connections between the battery and armature so that the voltage generated by the armature and battery will be in the same direction to build up the ignition circuit. 55
22. A system of the class described having an ignition circuit with a battery adapted to feed the same and an interrupter in operative relation thereto, a generating armature having two windings, one connected to feed the ignition circuit and one connected to charge the battery, the battery and first mentioned armature winding being in series with one another in said circuit, and a commutator reversing the connections between said first mentioned armature winding and the battery, whereby the voltage generated by said first mentioned armature winding and battery will be in the same direction to build up the ignition circuit. 60
23. A system of the class described having an ignition circuit with a battery adapted

- to feed the same and an interrupter in operative relation thereto, a generating armature having two windings, one connected to feed the ignition circuit, and one connected to charge the battery, an induction coil for feeding sparking devices, the induction coil, battery and said first mentioned armature winding being in series with one another in said circuit, and a commutator reversing the connections between the battery on one hand and the first mentioned armature winding and induction coil on the other hand, whereby the voltage generated by said first mentioned armature winding and battery will be in the same direction to build up the ignition circuit but the current through the induction coil will alternate in direction.
24. A system of the class described having an ignition circuit with a battery adapted to feed the same and an interrupter in operative relation thereto, a generating armature having two windings, one connected to feed the ignition circuit and one connected to charge the battery, an interrupter for the ignition circuit, the interrupter, battery and said first mentioned armature winding being in series with one another in said circuit, and a commutator reversing the connections between the battery on one hand and the first mentioned armature winding and interrupter on the other hand, whereby the voltage generated by said first mentioned armature winding and battery will be in the same direction to build up the ignition circuit but the current through the interrupter will alternate in direction.
25. A system of the class described having an ignition circuit with a battery, a generating armature and an induction coil with its primary in series therein, and a commutator reversing the connections between the battery and armature so that the voltage generated by the armature and battery will be in the same direction to build up the ignition circuit, the primary of the induction coil being on the battery side of the commutator so that it always builds up in the same direction.
26. A system of the class described having an ignition circuit with a battery, a generating armature and an induction coil with its primary in operative relation to said circuit, and a commutator reversing the connections between the battery and armature so that the voltage generated by the armature and battery will be in the same direction to build up the ignition circuit, the primary of the induction coil being on the battery side of the commutator so that it always builds up in the same direction, and connections whereby the secondary of the induction coil is adapted to supply sparking devices.
27. In a system of the class described a generating armature having two windings, a storage battery connected to be charged by one winding, an induction coil the secondary of which is adapted to supply sparking devices, said second armature winding and the primary of the induction coil being connected in circuit in series with the storage battery, an interrupter in series in said circuit, and a commutator acting to so connect the battery and said second armature winding that the voltage applied to said circuit by the second armature winding will always be in the same direction as that of the battery.
28. In a system of the class described a storage battery, generating means comprising a magneto armature winding and an armature winding connected to charge the battery, an ignition circuit having the battery and said magneto armature winding in series therein, a coil in inductive relation to said circuit for supplying sparking devices, and an interrupter and commutator in said circuit, said commutator acting to so connect the battery and magneto armature winding that the voltage of one is in the same direction as the voltage of the other in said circuit.
29. In a system of the class described a storage battery, generating means comprising a magneto armature winding and an armature winding connected to charge the battery, an ignition circuit having the battery and said magneto armature winding in series therein, an induction coil having its primary in series in said circuit and its secondary adapted to supply sparking devices, and an interrupter and commutator in said circuit, said commutator acting to so connect the battery and magneto armature winding that the voltage of one is in the same direction as the voltage of the other in said circuit.
30. In a system of the class described a storage battery, generating means comprising a magneto armature winding, an ignition circuit having the battery and said magneto armature winding in series therein, an induction coil having its primary in series in said circuit and its secondary adapted to supply sparking devices, and an interrupter and commutator in said circuit, said commutator acting to so connect the battery and magneto armature winding that the voltage of one is in the same direction as the voltage of the other in said circuit.
31. In a system of the class described a storage battery, generating means comprising a magneto armature winding and an armature winding connected to charge the battery, a work circuit connected to be supplied by the battery and said second armature winding, an ignition circuit having the

6
battery and said magneto armature winding in series therein, an induction coil having its primary in series in said circuit and its secondary adapted to supply sparking devices, and an interrupter and commutator in said circuit, said commutator acting to so connect the battery and magneto armature winding that the voltage of one is in

the same direction as the voltage of the other in said circuit. 10

In testimony whereof, I have signed my name to this specification.
